(57) **CLAIM**

We claim the ornamental design for an instrument stand, as shown and described.

DESCRIPTION

FIG. 1 is a front view of the instrument stand showing our new design;

FIG. 2 is a rear view thereof;

FIG. 3 is a top view thereof;

FIG. 4 is a bottom view thereof;

FIG. 5 is a left-side view thereof;

FIG. 6 is a right-side view thereof;

FIG. 7 is a perspective view thereof; and,

FIG. 8 is another perspective thereof.

The broken lines in the drawings are for illustrative purposes only and form no part of the claimed design.
